CLAIM

We claim the ornamental design for a bone fixation plate, as shown and described.

DESCRIPTION

FIG. 1 is a perspective view of a bone fixation plate in accordance with the present invention;
FIG. 2 is a front plan view thereof;
FIG. 3 is a rear plan view thereof;
FIG. 4 is a left side plan view thereof;
FIG. 5 is a right side plan view thereof;
FIG. 6 is a top plan view thereof;
FIG. 7 is a bottom plan view thereof;
FIG. 8 is a perspective view of another embodiment of a bone fixation plate in accordance with the present invention;
FIG. 9 is a front plan view thereof;
FIG. 10 is a rear plan view thereof;
FIG. 11 is a left side plan view thereof;
FIG. 12 is a right side plan view thereof;
FIG. 13 is a top plan view thereof; and,
FIG. 14 is a bottom plan view thereof.

The broken lines showing the remainder of the bone fixation plate are depicted to environment. None of the broken lines form a part of the claimed design.

1 Claim, 8 Drawing Sheets
